Letters Patent No. 1818 Dated Sept 14/1818.

Design for a Carpet Pattern.

The schedule referred to in these Letters Patent and making part of the same.

To all whom it may concern

Be it known, that I, Elemin J. Ney, of Lowell,
in the County of Middlesex and State of Massachusetts, have originated
and designed a new Pattern for Carpets or other fabrics, of which the
following is a full, clear and exact description, reference being had
to the accompanying drawings, making part of this specification.

A, in the centre is an oblong set figure surrounded by the

band of lace work 1. Extending from and completely surrounding this lace work, is a number of leaves, and enclosing this combination of leaves is the irregular band 2, composed of a succession of short lines.

By matching the four corners a figure is formed similar to A in the centre. The surroundings of the figure are formed by matching the corners are similar to those of the centre. The remainder of the design consists of a ground work of small blocks.

The colors employed for the different portions of the design, may be varied to suit the taste and wish of the manufacturer.
